UNITED STATES PATENT OFFICE

171,474

PRESS

Reuben E. Wissman, Minster, Ohio, assignor to
The Minster Machine Company, Minster, Ohio,
a corporation of Ohio

Application July 27, 1953, Serial No. 26,156

Term of patent 14 years

(Cl. D63—1)

To all whom it may concern:

Be it known that I, Reuben E. Wissman, a citizen of the United States and a resident of Minster, Auglaize County, State of Ohio, have invented a new, original, and ornamental Design for a Press, of which the following is a specification, reference being had to the accompanying drawing, forming a part thereof, wherein:

Figure 1 is a front elevational view of a press embodying my new design;

Figure 2 is a right side elevational view of the press looking in from the right side of Figure 1;

Figure 3 is a left side elevational view of the press looking in from the left side of Figure 1; and

Figure 4 is a rear elevational view of the press.

I claim:

The ornamental design for a press, substantially as shown.

REUBEN E. WISSMAN.
